TOY ANIMAL FIGURE

George W. Geromanos, Rahway, N. J., assignor to Geromino Toy Company, Inc., Rahway, N. J., a corporation of New Jersey

Application June 6, 1949, Serial No. 3,071

Term of patent 7 years

(Cl. D34—2)

To all whom it may concern:

Be it known that I, George W. Geromanos, a citizen of the United States, residing at Rahway, in the county of Union and State of New Jersey, have invented a new, original, and ornamental Design for a Toy Animal Figure, of which the following is a specification, reference being had to the accompanying drawing, forming part thereof.

I claim:

The ornamental design for a toy animal figure, as shown.

GEORGE W. GEROMANOS.
